UNITED STATES PATENT OFFICE.

ALBERT H. STEBBINS, OF LOS ANGELES, CALIFORNIA.

CONCENTRATOR DECK.

Application filed August 10, 1926. Serial No. 128,376.

This invention relates to improvements in the construction of concentrator decks.

Concentrator decks as constructed heretofore to treat ores or other comminuted materials in the dry state, are usually provided with a deck surface that is supported at a transverse inclination, and riffles extending diagonally over the deck surface serve to direct the concentrates toward the upper side 10 of the deck while the tailings flow laterally over the riffles toward the lower side of the deck.

The travel of the tailings transversely of the deck is effected by the lateral inclination 15 of the deck surface, and by the strength of the air currents passing upwardly through apertures in the deck surface, but difficulty has been experienced heretofore in promoting the desired transverse flow of the tailings without employing either a greater transverse inclination of the deck, or a greater volume of air than is desired to effect the stratification of the materials. It has therefore been necessary heretofore to 20 carefully adjust the transverse inclination of the deck and the strength of air currents employed to accommodate the size of the materials being treated, and the range in size of the materials that could be satisfactorily treated upon a deck having a particular adjustment has been quite limited.

The present invention is therefore directed to a novel deck construction which is adapted to treat materials that may vary in size throughout a wide range and which 35 also requires less attention on the part of the operator, and gives better results than the concentrator decks employed heretofore.

One important feature of the present invention resides in a concentrator deck that is supported at a transverse inclination, as is usual, but which differs from the decks provided heretofore in that a pan or basin 40 is formed adjacent the lower side of the deck to receive and confine the tailings for a sufficient length of time to cause the fine concentrates contained in the tailings to work down under the tailings to the deck surface, whereupon they are directed out 45 from under the mass of tailings toward the upper side of the deck by the riffles.

The pan or basin feature just mentioned makes it unnecessary to vary the transverse inclination of the deck to accommodate different size materials; this feature is therefore well adapted for use in either a single

deck, or in a twin deck construction in which the deck surface is built into the deck as a rigid, non-adjustable structure.

Another feature of the invention therefore 60 resides in a twin-deck construction consisting of a single supporting frame provided with a pair of oppositely inclined deck surfaces that are formed rigidly with the supporting frame. 65

Still another feature of the invention resides in skimmers associated with one or more of the riffles near the concentrate wall and which are adapted to separate the coarse 70 from the fine concentrates.

Other features of the invention and novel combination of parts in addition to the above will be hereinafter described in connection with the accompanying drawings 75 which illustrate good practical forms of the invention.

In the drawings,—

Fig. 1 is a side elevation of a table concentrator provided with a deck constructed in accordance with the present invention; 80

Fig. 2 is a top plan view of the deck shown in Fig. 1;

Fig. 3 on an enlarged scale is a sectional view taken on the line 3—3 of Fig. 2;

Fig. 3^a is a view similar to Fig. 3, but 85 shows a modification wherein the upward bend imparted to a portion of the deck in Fig. 3 is omitted.

Fig. 4 is a top plan view of a concentrator deck having twin deck surfaces with the concentrate walls lying adjacent each other; 90

Fig. 5 is a concentrator deck provided with twin deck surfaces wherein the concentrate walls are disposed at the opposite sides of the deck; 95

Fig. 6 is a sectional view taken on the line 6—6 of Fig. 4;

Fig. 7 is a sectional view taken on the line 7—7 of Fig. 5;

Fig. 8 on an enlarged scale is a plan view 100 of a fragmentary portion of the deck shown in Fig. 2;

Fig. 9 is a sectional view taken on the line 9—9 of Fig. 8;

Fig. 10 is a plan view somewhat similar 105 to Fig. 8, the tailing discharge gate being omitted; and

Fig. 11 is a sectional view taken on the line 11—11 of Fig. 10.

The pan or basin construction which constitutes an important feature of the present invention may be employed in connection

with decks of various shapes, but is best adapted for use upon relatively long narrow decks such as shown in the drawings.

The deck surface as is usual is supported at a transverse inclination and to this end in the construction shown in Figs. 1, 2 and 3 the lower side of the deck is secured to the deck supporting carriage 10 by a row of hinges 11, and the upper or concentrate side of the deck is supported in spaced relation to the carriage 10 by the threaded posts 12 having the adjustable nuts 13 for varying the transverse inclination of the deck. This construction however, whereby the transverse inclination of the deck may be varied, is not essential in the present construction since it is unnecessary to vary this transverse inclination to treat different size materials.

Any suitable means might be provided for supporting the deck for vibratory movement in the direction of its length, and in the construction shown in Fig. 1 the carriage 10 is supported by the concentrator frame consisting of the uprights 14, to which the longitudinally extending side rails 15 are secured, and upon the deck supporting frame thus formed are mounted the grooved bearing blocks 16 adapted to receive balls or rollers 17, the upper portions of which extend into the grooved bearing blocks 18 that are secured to the under face of the carriage 10.

Any suitable means might be employed for imparting a progressive vibratory movement to the deck, and a simple construction to this end is shown in Fig. 1, and consists of the operating cable 19 which serves to yieldingly move the deck in a right-hand direction, while the deck is pulled in a left-hand direction by the power actuated cable 20.

One end of the operating cable 19 is secured to a threaded pipe or the like 21 which is adjustably secured by nuts 22 to a bracket 23 rigidly secured to the carriage 10. An intermediate portion of this cable passes around a grooved sheave 24 supported by the transversely extending shaft 25, and the lower end of the cable 19 is connected to a spring 26 that exerts a continuous downward pull upon the cable.

The cable 20 has one end rigidly secured to a pipe or tube 27 that is adjustably secured to a bracket 28 fastened to the under side of the carriage 10, and the adjacent ends of the pipes 21 and 27 are preferably connected by a turn buckle 29. An intermediate portion of the cable 20 extends around a grooved sheave 30 mounted upon a shaft 31, and the portion of the cable extending from the lower side of the sheave 30 is bent around a grooved sheave 32 and the lower end of this cable is anchored to the supporting frame by the adjustable means 33. The sheave 32 is mounted on an eccentric

34 which is rigidly secured to the power driven shaft 35. The arrangement is such that rotation of the power shaft will turn the eccentric within the sheave 32 to move the latter through an orbital path to thereby tension and slack off the cable 20. This will serve to move the deck back and forth in the well known manner, and by varying the tension of the spring 26 the progressive movement imparted to the deck may be made as energetic as desired.

The materials to be treated are delivered to the deck surface 36 by the hopper 37 having the adjustable gate 38 for controlling the flow of the materials to the deck surface. Air under pressure may be supplied to the chamber 39 below the deck surface by a fan 40. The upper side of the deck is provided with the concentrate wall 41 which is provided with the usual buffer blocks 42 against which the concentrates are directed by the riffles 43, and an inclined wall 44 is preferably provided and extends downwardly from the feed hopper to the lower side of the deck, as shown.

As above stated, an important feature of the present invention resides in the construction whereby a pan or basin is formed along the lower side of the deck-supporting surface so that the tailings are confined in this basin until the fine concentrates suspended in the tailings are given an opportunity to settle. The basin or pan may be variously constructed so that it will confine a relatively large amount of tailings throughout the operation of the concentrator, and in the construction shown the pan or basin effect is produced by providing a relatively tall wall 45 which extends a substantial distance along the lower side of the deck and which constitutes a retaining wall against which the tailings may pile up, as clearly shown in Figs. 3 and 3^a.

The result of the construction just described is such that as the tailings flow transversely across the deck over the riffles 43 they will pile up against the wall 45, and while resting against this wall they will undergo a panning action due to the vibratory movement imparted to the deck and this will cause the small concentrates suspended within the tailings to work downwardly under the mass of tailings, and upon reaching the deck surface they will be directed out from under the mass of tailings towards the upper side of the deck by the inclined riffles 43. The bed of tailings retained in the basin preferably has a depth several times as great as the height of the riffles extending across the basin, as will be apparent from Fig. 3 and Fig. 3^a, and the riffles may be completely buried under the bank of materials for a distance more than half way up the inclined deck as shown. It will therefore be seen that the panning

action just mentioned will serve to remove from the tailings the fine values which would be lost if the present panning construction were not employed.

5 As above stated, the panning feature of the present invention is best adapted for use upon a relatively long narrow deck. This construction is desirable in order that the retaining wall 45 may extend a sufficient 10 distance along the lower side of the deck to form a long pan or basin which will give the concentrates ample opportunity to settle out of the tailings before the latter are permitted to escape from the basin. A long 15 narrow deck is further desirable since it causes the bank of tailings resting against the wall 45 to extend laterally over the deck surface a substantial distance so that a large portion of the deck surface is covered by a 20 relatively thick bank of tailings. This it is found stabilizes the action of concentrating or stratifying the materials, and as a result materials varying in size throughout 25 a wide range may be thoroughly classified upon a long narrow deck having the panning construction of the present invention. Furthermore the transverse inclination imparted to the deck surface does not need 30 to be adjusted with the same degree of care which has been necessary heretofore, since the bank of tailings extending laterally over the deck surface renders the materials less sensitive to changes in the transverse inclination of the deck than heretofore.

35 It may be desirable to prevent the formation of a relatively deep pocket adjacent the tailing retaining wall 45. This is accomplished by bending a portion of the deck 36 lying adjacent the wall 45 upwardly, as indicated by 46 in Fig. 3, instead of 40 continuing the slope of the deck to the wall 45 as in Fig. 3^a, but in either case the riffles 43 should extend across the basin formed at the lower side of the deck so that 45 they will direct the concentrates out of this basin towards the concentrate wall.

After the tailings have traveled a sufficient distance along the retaining wall 45 to give the concentrates suspended therein ample time to settle, they are permitted to escape from the discharge end of the wall 45 into a tailing receiving trough 47, and the discharge end portion of the wall 45 is preferably tapered as at 48, whereby the 50 materials piled up against this wall are caused to flow gradually over such tapered portion 48. The portion of the concentrate wall disposed near the discharge end of the deck, preferably slopes downwardly as at 49 to thereby increase the number of riffles that terminate against the concentrate wall. The concentrates traveling along the concentrate wall may be drawn off through 55 any desired number of adjustable gates 50 to fall into the concentrate trough 51.

As is preferably employed to promote separation of the materials being treated upon the deck surface and to this end the deck is provided with the air apertures 52 which may be formed only in that portion 70 of the deck lying near the feed hopper, or may extend over substantially the entire deck, as desired.

It is highly desirable to dispose of the large concentrates as promptly as possible 75 so that the remaining portion of the deck may be utilized to separate the finer concentrates from the tailings; it is therefore desirable to use relatively strong air currents adjacent the feed hopper which will 80 force over the riffles everything except the large concentrates.

As above pointed out it is unnecessary to vary the inclination of the deck to accommodate different grades of materials, since 85 by employing the basin construction described a standard transverse inclination will serve to effect the desired separation of various grades of material. The present construction is therefore peculiarly well adapted 90 for employment in a deck having oppositely inclined or twin deck surfaces as shown in Figs. 4 and 5. The concentrate sides of the two decks may lie adjacent each other as shown in Figs. 4 and 6, or the concentrate 95 walls may be disposed at the opposite sides of the deck, as shown in Figs. 5 and 7. In the construction shown in Fig. 6 the oppositely inclined deck surfaces 53 are provided 100 with a common concentrate wall 54 having the buffer blocks 55, and if the same materials are to be treated upon each of the deck surfaces 53, then it is unnecessary to extend the concentrate wall 54 throughout the entire length of the deck, since there is no objection to the concentrates upon the two 105 deck surfaces coming in contact with each other. If, however, materials of different grades are treated upon the different deck surfaces 53 then the feed hopper 56 should 110 be provided with a central partition 57 to prevent mixing of the materials and a continuous wall 54 should be used. The operation of the materials upon each of the decks 115 53 shown in Figs. 4 and 6 is substantially the same as described in connection with Figs. 1, 2 and 3, and the concentrates are drawn off through two or more gates 58 into the concentrate troughs 59, while the tailings, upon escaping from the discharge end 120 of the tailing retaining walls 60, fall into the tailing receiving troughs 61.

In the construction shown in Figs. 5 and 7 the materials to be treated are fed to the oppositely inclined deck surfaces 62 by the feed hoppers 63 and the concentrates are directed against the concentrate walls 64 by the inclined riffles 43. These concentrates upon approaching the discharge end of the deck may escape through one or more gates 130

85 into the concentrate troughs 66. The tailings that accumulate along the central portion of the double deck construction travel lengthwise of the deck until they escape into the tailing receiving trough 67, and it will be understood that the thick layers of tailings traveling along the central portion of the twin deck construction of Fig. 5 undergo the panning action above described whereby the fine concentrates are caused to work downwardly to the deck surface so that they are directed out from under the mass of tailings towards the concentrate walls.

15 In some cases it is desirable to separate the coarse and fine values traveling along the riffles so that the coarse values may be removed from the deck while the fine values are permitted to remain to undergo further treatment. A good practical construction to this end is shown in Figs. 8 to 11 inclusive wherein the skimmer 68 is shown as secured to a riffle 43 adjacent a gap 69 in the riffle. The scraper 68 has a beveled lower face 70 which is supported in spaced relation to the deck surface 36 and as a result the fine concentrates are permitted to pass under the beveled edge 70 of the skimmer to flow laterally across the deck under the influence of its transverse inclination, while the coarser concentrates which fail to pass under the skimmer are prevented from escaping from the guiding riffles by the skimmer 68 and by the guide wall 71. As a result of the construction just described the large concentrates will be directed towards the concentrate discharge opening 72 having the adjustable gate 50 while the tailings which escape under the skimmer will remain upon the deck surface for further treatment. It will be apparent that a deck may be provided with any number of the skimmers 68 just described, and that one may be provided adjacent each discharge gate 50, or if desired 45 they may be provided even where the discharge gates are not used; in which case they will serve to retard or hold back the coarse concentrates, while permitting the fine concentrates to escape from one riffle to the next 50 for further treatment.

A concentrator deck when constructed in accordance with the present invention not only removes the concentrates more completely than heretofore by subjecting the tailings to a thorough panning action, but the bank of tailings spread out over a substantial portion of the deck surface serves to stabilize the operation of the deck so that materials varying throughout a wide range 60 in size may be treated upon the deck at the same time with excellent results. Furthermore it is unnecessary to change the transverse inclination of the deck to accommodate different size materials and the deck is easier

to operate with efficient results, and various other advantages are secured.

What is claimed is:

1. A concentrator deck, comprising in combination, a deck surface that is supported at a transverse inclination and which is adapted to be vibrated in the direction of its length to advance the materials lengthwise of the deck, riffles extending diagonally over the deck surfaces to direct the concentrates toward the upper side of the deck, and a material retaining wall extending a substantial distance along the lower side of the deck and constructed to form a concentrate settling basin along the lower side of the deck and in which a deep layer of tailings is confined while they are subjected to a panning operation, said wall being arranged so that it extends lengthwise of the deck and does not slope down the inclined deck.

2. A concentrator deck, comprising in combination, a deck surface that is supported at a transverse inclination and for vibration in the direction of its length to advance the materials lengthwise of the deck and which is provided with a concentrate settling basin extending along the lower side of the deck and constructed to confine the tailings in a deep layer while they travel a substantial distance along the lower side of the deck to cause them to undergo a panning operation, and riffles arranged to direct the concentrates that settle in the basin out from under the tailings and toward the upper side of the deck, said basin being formed to extend lengthwise of the deck in substantially a horizontal plane so that it does not slope down the inclined deck from one end toward the other.

3. A concentrator deck, comprising in combination, a deck surface that is supported at a transverse inclination, inclined riffles extending over the deck surface to direct the concentrates toward the upper side of the deck, means for vibrating the deck in the direction of its length to advance the materials along the same, and the deck being constructed to provide a concentrate settling basin upon the deck surface that extends a substantial distance along the lower side of the deck in the direction of the deck movement so that it does not slope down the transversely inclined deck surface and adapted to retain in the basin a bed of tailing having a depth several times as great as the height of the riffles extending across the basin so that the materials in the basin will be subjected to a panning action.

4. A concentrator deck, comprising in combination, a long narrow deck surface, the width of which is approximately the same from its material receiving end to a position near its discharge end and which is supported at a transverse inclination and

for movement in the direction of its length to advance materials lengthwise of the deck, riffles extending diagonally over the deck surface to direct concentrates toward the 5 upper side of the deck, and a material retaining wall extending along the lower side of the deck and arranged to form upon the lower portion of the deck surface a concentrate settling basin that extends lengthwise 10 of the deck to a position near the discharge end thereof and in which the tailings are subjected to a panning action, said wall being arranged to extend lengthwise of the lower side of the deck so that it does not 15 slope down the inclined deck.

5. A concentrator deck, comprising in combination, a deck surface that is supported at a transverse inclination, riffles extending over the deck surface to direct the concentrates toward the upper side of the deck, 20 a material retaining wall extending along the lower side of the deck and constructed to confine the tailings and to form a concentrate settling basin along the lower side 25 of the deck, and the deck surface lying adjacent said wall being bent upwardly at an angle to the remaining portion of the deck surface to decrease the depth of the tailings adjacent said wall.

30 6. A concentrator deck, comprising in combination, a deck surface that is supported at a transverse inclination and for vibratory movement in the direction of its length to advance the materials lengthwise 35 of the deck, riffles extending diagonally over the deck surface to direct the concentrates toward the upper side of the deck, a material retaining wall extending a substantial distance along the lower side of the deck 40 surface and constructed to confine the tailings and to form a concentrate settling basin along the lower side of the deck, and in which the materials are subjected to a panning action, and said wall being arranged 45 so that it extends lengthwise of the deck, but does not slope down the inclined deck and the height of which is gradually decreased in the direction of its discharge end.

7. A concentrator deck, comprising in 50 combination, a deck surface that is supported at a transverse inclination and having a concentrate wall extending along the upper side of the deck, riffles extending over the deck surface toward the concentrate wall 55 and some of the riffles having a portion of their walls cut away to release the concentrates traveling along the riffles, and skimmers supported in spaced relation to the deck surface adjacent said cut-away portions and 60 adapted to permit the fine concentrates to flow laterally down the deck while they prevent the coarse concentrates from flowing laterally with the fine concentrates.

8. A concentrator deck, comprising in 65 combination, a deck surface that is supported

at a transverse inclination and having a concentrate wall extending along the upper side of the deck, riffles extending over the deck surface toward the concentrate wall, means for discharging the concentrates from the 70 deck at a point along the concentrate wall, and a skimmer associated with one of the riffles for directing the coarse concentrates toward the discharge means while permitting the fine concentrates to escape from the 75 riffles laterally down the deck.

9. A concentrator deck, comprising in combination, a deck surface that is supported at a transverse inclination and having a concentrate wall extending along the 80 upper side of the deck, riffles extending over the deck surface toward the concentrate wall and a skimmer associated with one of the 85 riffles and supported in spaced relation to the deck so that it separates the coarse from the fine concentrates.

10. A concentrator deck, comprising in combination, a long narrow deck surface that is supported at a transverse inclination and for vibratory movement in the direction 90 of its length to advance the materials lengthwise of the deck, riffles extending diagonally over the deck surface to direct concentrates toward the upper side of the deck, a material retaining wall extending a substantial 95 distance along the lower side of the deck in the direction of the deck movement so that it does not slope down the transversely inclined deck surface and arranged to retain upon the deck a thick layer of materials 100 under which the riffles are completely buried for a distance more than half-way up the inclined deck surface, and means for vibrating the deck to subject the materials piled up 105 against said wall to a panning operation to work the values down through the materials into engagement with the riffles.

11. A concentrator deck, comprising in combination, an apertured deck surface that is supported at a transverse inclination and for vibratory movement in the direction of its length, riffles extending diagonally over the deck surface to direct the concentrates toward the upper side of the deck, a material retaining wall extending a substantial 110 distance along the lower side of the deck in the direction of the deck movement so that it does not slope down the transversely inclined deck surface and arranged to retain upon the deck a thick layer of materials, means for vibrating the deck to advance the materials along the deck surface and to subject the bank of materials piled up against said wall to a panning action, and means for forcing air up through the apertured deck surface 115 and bank of materials resting thereupon to promote said panning operation.

In testimony whereof, I have signed my name to this specification.

ALBERT H. STEBBINS.
